BENDING MACHINE

John F. Fischer, Detroit, Mich., assignor, by mesne assignments, to L. A. Young Spring & Wire Corporation, Detroit, Mich., a corporation of Michigan

Application December 2, 1935, Serial No. 52,497

19 Claims. (Cl. 153—40)

This invention relates to improvements in bending machines.

The main objects of this invention are:

First, to provide a metal bending machine characterized by a slow movement of the form during the bending of certain portions and a rapid movement during the simpler bending operation on other portions.

Second, to provide novel means for reciprocating a bending form during the rotation thereof.

Third, to provide improved mandrel supporting means for a metal strip bending machine.

Fourth, to provide reciprocating means for the form of the metal bending machine, characterized by the simplicity and efficiency thereof.

Objects relating to details and economies of my invention will appear from the description to follow. The invention is defined and pointed out in the claims.

20 A structure which is a preferred embodiment of my invention is illustrated in the accompanying drawings, in which:

Fig. 1 indicates a perspective view of a machine embodying my invention.

25 Fig. 2 indicates a top plan view of the slidable bed plate and rotatable table included in my invention, the bending fixture and mandrel being removed and successive positions of the bed plate being indicated in dotted lines.

30 Fig. 3 is a sectional view taken on line 3—3 of Fig. 1 with portions omitted and broken away.

Fig. 4 is a view along the line 4—4 of Fig. 5, illustrating details of my improved mandrel carrier.

35 Fig. 5 is a sectional view along the line 5—5 of Fig. 4.

Fig. 6 is a view of a formed part bent by my machine with the form illustrated, the part being shown after being welded.

40 The machine of the present application is an improvement on the machine embodied in my prior Patent No. 1,970,694, dated August 21, 1934, and differs primarily therefrom in that it is provided with means for reciprocating the work

45 supporting bed plate mounted on a rotatable table so as to furnish a rapid movement of the bending form past the mandrel at points where there is no substantial bending of the work, it being merely laid up against the form. At points

50 where there is continual and abrupt bending of the metal strip such as the corners of an elongated rectangular shaped window frame or moulding, the form is passed slowly by the bending mandrel due to the fact that there is no reciprocating movement imparted thereto,

I have found that greatly improved results are attained by such variations in speed of travel of the form since if a machine for producing a rectangular window frame is operated slowly enough to produce abruptly rounded portions in a safe manner, its travel at the elongated straight or slightly bent portions of the frame is too slow for desired speed of production. Likewise if the speed of the entire operation of a form having rotative movement only is stepped up so as to provide the necessary speed for the complete operation, the bending of a strip of conformed cross section around the abrupt corners is so rapid that fracturing of the metal results.

With the above objects in view I have equipped the bed plate supporting the bending form of my machine with cam tracks at either end cooperating with a roller mounted on a stationary part of the machine for the purpose of reciprocating the plate and form rectilinearly at the same time that they are being given a rotative movement by means supplied for that purpose.

My invention further embodies an improved mandrel carrier to cooperate with the form during the compound movement imparted to the form.

Referring to the drawings, the reference numeral 1 indicates a suitable work supporting table mounted in conjunction with a supporting frame or table 2 for the operating means comprising my invention. A drive shaft 3 is arranged underneath support 2 to actuate a bevel gear 4 meshing with bevel gear 5 which is rigidly secured to a rotating table 6 carried on support 2 by means of a depending annular rib-like slide 35 traveling in the annular groove-like way 8 in support 2.

Rigidly mounted on rotating table 6 by means of screws 9 I provide side guide ways or members 10 having undercut longitudinal grooves 11 in which are received horizontal flanges 12 of a slidable form bed plate 13. By the above construction a bed plate 13 is capable of having imparted thereto a sliding reciprocating motion with respect to rotatable table 6 and receives the same rotative movement as is imparted to table 6 or rotates with the table. Suitably mounted on the sliding bed plate 13 as by means of screws 14 is a bending form 15 having a peripheral channel therein adapted to receive the work, in this embodiment the metal strip 16, and having an approximately elongated rectangular form similar to the shape of the frame formed from the bent strip 16, as indicated in Fig. 6. It will be apparent that other outlines may be bent by 55

my machine and that strips having various cross sections may be operated on by simply supplying appropriate forms to the plate 13 and providing appropriate mandrels.

5 At the opposed ends of the sliding form bed plate 13 I mount cam elements 17 having secured thereto by cross pieces 18 the further cam elements 19. The elements 17 and 19 constitute cam tracks in which roller 20 is received, roller 10 20 being suitably mounted on the stationary frame or table 2. The purpose of the cam tracks 17 and 19 and the roller 20 is to push plate 13 and the form carried thereby longitudinally in the side guides 10 while the plate is being rotated. As a result of the combined longitudinal movement and rotation of plate 13, it will be seen that the travel thereof is considerably more rapid than when the plate has a rotation alone imparted to it.

15 20 I have described the longitudinal movement as being supplied by cam tracks and a roller. However, it will be apparent that this result may be accomplished in various ways, viz., through routed grooves, or slides, or racks and pinions, or 25 by air cylinders, etc.

For guiding the bed plate 13 during the purely rotary movement of the same, I provide a plurality of rollers 21 mounted in blocks 22 suitably spaced on frame 2. The rollers coat with grooves 30 23 in the bottom of the bed plate 13 and the spacing of the rollers is such that at all times during the purely rotative movement of the plate there is a roller 21 in groove 23. Thus, in Fig. 1, the cam tracks 19 have completed their function of imparting a longitudinal movement to plate 13 and roller 21 is entering groove 23 to guide plate 13 during its circular movement with respect to the mandrel.

My machine is provided with the usual single 40 revolution mechanism for stopping the rotation thereof after a strip 16 has been bent, comprising cams 24 on rotating table 6, links 25, 26, lever 27, 45 slideable rod 28 and spring 29. This structure forms no part of my invention.

45 Mounted on the frame 2 adjacent rotating table 6 I dispose a vertical shaft 30 having pivoted thereon a horizontally extending arm 31, the arm being provided at the pivotal point with a bracket 32 in which is threaded an adjusting screw 33 by 50 means of which the height of arm 31 on shaft 30 may be adjusted.

At the free end of arm 31 I swivel a mandrel support spindle 34 having an enlargement or head 55 35. The apertured retaining plate 36 holds the spindle 34 for swiveling movement in arm 31 by its engagement with the head of the spindle, and screws 37 secure the retaining plate to arm 31. A spacing member or sleeve 38 under cut at 39 is arranged on the spindle 35 beneath the plate 36. 60 Secured to spacing member 38 by means of screws 40 (Fig. 4) is an apertured guide plate 41 having slots 42 therein to receive swiveling guide pins 43 which depend into curved recesses in the mandrel carrier 44.

65 The mandrel carrier, as indicated in dotted lines in Figs. 4 and 5, is recessed at 45 to receive spindle 34 and has a groove 46 extending longitudinally thereof in which the tongue 47 of a suitably shaped mandrel 48 is mounted. At its lower end 70 the mandrel support pin 34 is provided with an enlarged pilot roller 49 which cooperates with a track or ledge 50 on the upper surface of the bed plate 13. Plate 13 likewise carries wear plates 51 on which the face end of strip 16 slides while it is 75 being bent. Ledge 50, as will be seen, acts to

forcibly maintain mandrel 48 in the channel form 15 during the passage of the form past the mandrel.

Referring to Fig. 4, the tail end 52 of mandrel 48 is illustrated as being rounded to permit the passage of the mandrel inside the conformed work 16. In the above description of the mandrel and supporting means therefor, it will be apparent that mandrel 48 and its carriage 44 have a swiveling movement due to the mounting of the spindle 10 34, arm 31 and also a further swiveling movement provided by the guide pins 43 in slots 42. A completely free and universal pivoting of the mandrel 47 about abrupt turns is thus assured while pilot roller 49 and track or ledge 50 hold the mandrel 15 against the strip in the form channel.

I provide means comprising a chain or cable 53 passing over a pulley 54 mounted in an upwardly extending bracket 55 secured to frame 2 and having a weight 56 attached to the end thereof for yieldingly urging arm 31 and the mandrel devices carried thereby outwardly from the form 15.

20 Interiorly of the form 15 a clamping means for clamping an end of the work 16 against the form is shown, comprising a block 57 and handle member 58 which, when actuated, operates a link 59 and strip clamping element 60 by means of a cam mechanism or toggle mechanism such as shown in my Patent No. 1,970,694, or other suitable means.

25 In operation a piece of work 16 of desired cross section is clamped by element 60 against form 15, the mandrel 47 having been inserted in the strip. The table 6 is rotated and the form travels in operative relation to the mandrel. Due to the 30 action of roller 20 and cam track 19 at the points where a relatively slight bend is to be imparted to the work, a fast motion is given to the form during its travel. However, when an abrupt bend is to be formed, cam track 19 leaves roller 20 and the motion is a purely circular one, the table 40 carrying the form being supported by rollers 21 in groove 23. This motion is a relatively slow one and permits the material of the work to flow properly, thereby accomplishing a more satisfactory and smooth bend. After the abruptly bent portion of the work has been formed cam tracks 19 at the opposite end of the table come into cooperation with roller 20, with the result that the table is rapidly reciprocated reversely to the direction of its first reciprocation and the elongated portion of 50 the strip 16 is laid in the channeled form 15.

55 My improved mandrel 48 and swiveling connection therefor contribute materially to the accomplishment of the objects of my invention by furnishing a free movement of the mandrel in its working relation to the form channel.

I have illustrated and described my improvements in an embodiment which I have found very practical. I have not attempted to illustrate or describe other embodiments or adaptations as it is believed this disclosure will enable those skilled in the art to embody or adapt my improvements as may be desired.

Having thus described my invention what I claim as new and desire to secure by Letters 65 Patent is:

60 1. A metal bending machine comprising a rotatable table, an elongated bed plate slidably mounted on said table, a form fixed on said bed plate, an arm pivotally mounted adjacent said table, a mandrel swiveled in the end of said arm to cooperate with said form, means surrounding the form in uniform spaced relation thereto for maintaining the mandrel in cooperation with the form, pilot means associated with the mandrel 70 75 75

and coacting with said means, means for clamping the end of a strip of work to said form, and means for imparting a motion of pure rotation to said form during a substantial portion 5 of each revolution of the table and for imparting a combined movement of rotation and translation to the form during another portion of the revolution of the table, said last named means comprising a roller positioned at the end of said 10 table for sliding the form longitudinally during a portion of the rotation thereof and cam tracks on the table coacting intermittently with said roller, whereby the work is rapidly pressed between said form and mandrel during the combined longitudinal and rotative movement of the form and slowly during the rotative movement thereof.

2. A metal bending machine comprising a rotatable table, a bed plate slidably mounted on 20 said table, a form fixed on said bed plate, an arm pivotally mounted adjacent said table, a mandrel swiveled in the end of said arm to cooperate with said form, means surrounding the form in uniform spaced relation thereto for maintaining 25 the mandrel in cooperation with the form, pilot means associated with the mandrel and coacting with said means, and means for imparting a motion of pure rotation to said form during a substantial portion of each revolution of said 30 table and for imparting a combined movement of rotation and translation to the form during another portion of the revolution of the table, said last named means comprising cam tracks coacting with a roller positioned at the end of said table 35 for sliding the form longitudinally during the rotation thereof, whereby the work is rapidly pressed between said form and mandrel during a portion of the combined longitudinal and rotative movement of the form and slowly during the 40 rotative movement thereof.

3. A metal bending machine comprising a rotatable table, a bed plate slidably mounted on said table, a form fixed on said bed plate, an arm pivotally mounted on said table, a mandrel swiveled in the end of said arm to cooperate with 45 said form, means surrounding the form in uniform spaced relation thereto for maintaining the mandrel in cooperation with the form, pilot means associated with the mandrel and coacting with said means, and means comprising cam tracks coacting intermittently with a roller positioned 50 at the end of said table for sliding the form longitudinally during a portion of the rotation thereof, whereby the work is rapidly pressed between said form and mandrel during the combined longitudinal and rotative movement of the form and slowly during the 55 rotative movement thereof.

4. A metal bending machine comprising a rotatable table, a form slidably mounted on said 60 table, an arm pivotally mounted adjacent said table, a mandrel swiveled in the end of said arm to cooperate with said form, means surrounding the form in uniform spaced relation thereto for 65 maintaining the mandrel in cooperation with the form, pilot means associated with the mandrel and coacting with said means, and means for imparting movement of pure rotation to said form during a substantial portion of each revolution of 70 the table and for imparting a combined movement of rotation and translation to the form during another portion of the revolution of the table, said means comprising cam tracks coacting intermittently with a roller positioned at the end of 75 said table for sliding the form longitudinally dur-

ing a portion of the rotation thereof, whereby the work is rapidly pressed between said form and mandrel during the combined longitudinal and rotative movement of the form and slowly during the rotative movement thereof.

5. A metal bending machine comprising a rotatable table, a form slidably mounted on said table, an arm mounted adjacent said table, a mandrel swiveled in the end of said arm to cooperate with said form, means surrounding the form in uniform spaced relations thereto for maintaining the mandrel in cooperation with the form, pilot means associated with the mandrel and coacting with said means, and means comprising cam tracks coacting intermittently with a roller positioned at the end of said table for sliding the form longitudinally during a portion of the rotation thereof, whereby the work is rapidly pressed between said form and mandrel during the combined longitudinal and rotative movement of the form and slowly during the rotative movement thereof.

6. A metal bending machine comprising a rotatable table, a form slidably mounted on said table, a mandrel swiveled to cooperate with said form, means surrounding the form in uniform spaced relation thereto for maintaining the mandrel in cooperation with the form, pilot means associated with the mandrel and coacting with said means, and means comprising cam tracks coacting intermittently with a roller positioned at the end of said table for sliding the form longitudinally during a portion of the rotation thereof, whereby the work is rapidly pressed between said form and mandrel during the combined longitudinal and rotative movement of the form and slowly during the rotative movement thereof.

7. A metal bending machine comprising a rotatable table, a form slidably mounted on said table, an arm pivotally mounted adjacent said table, a mandrel swiveled in the end of said arm to cooperate with said form, means for maintaining the mandrel in cooperation with the form, pilot means associated with the mandrel and coacting with said means, and means comprising cam tracks coacting with a roller positioned at the end of said table for sliding the form longitudinally during a portion of the rotation thereof, and further means to prevent longitudinal movement of the form during another and a substantial portion of the movement of the form whereby the work is rapidly pressed between said form and mandrel during the combined longitudinal and rotative movement of the form and slowly during the rotative movement thereof.

8. A metal bending machine comprising a rotatable table, a form slidably mounted on said table, a mandrel cooperating with said form, means for maintaining the mandrel in cooperation with the form, and means for imparting a motion of pure rotation to said form during a substantial portion of each revolution of the table and for imparting a movement of combined rotation and translation to the form during another portion of the rotation of the table.

9. A metal bending machine comprising a rotatable table, a form slidably mounted on said table, a mandrel cooperating with said form, and means for imparting a motion of pure rotation to said form during a substantial portion of each revolution of the table and for imparting a movement of combined rotation and translation to the form during another portion of the rotation of the table.

10. In a metal bending machine, an elongated

- 5 rotatable and slidable form, means for rotating and sliding the form, means for clamping the end of a strip against said form, and means adapted to press the strip against said form during the 10 movement of the form, comprising a swiveled elongated mandrel, a carrier therefor, and a guide plate having slots therein and pins received in said mandrel and guided in said slots for guiding the swiveling movement of said mandrel.
- 10 11. In a metal bending machine, a rotatable and slidable form, means for rotating and sliding the form, and means adapted to press the strip against said form during the movement of the form, comprising a swiveled elongated mandrel, a carrier therefor, and a guide plate having slots therein and pins received in said mandrel and guided in said slots for guiding the swiveling movement of said mandrel.
- 15 12. In a metal bending machine, a rotatable and slidable form, means for rotating and sliding the form, and means adapted to press the strip against said form during the movement of the form comprising a swiveled mandrel, and a guide plate having slots therein and pins received in said mandrel and guided in said slots for guiding the swiveling movement of said mandrel.
- 20 13. In a bending machine, the combination with a rotatable table, a form bed plate mounted on said table for reciprocation transversely of the axis of the table, a form on said bed plate, means for clamping an end of the work to the form, a mandrel mounted for movement to and from the axis of the table, a track concentric of said form for supporting said mandrel in operative relation thereto as the form is rotated, means for intermittently imparting a reciprocating movement to said form bed plate as the table revolves comprising cam ways carried by said bed plate and a cam follower with which said cam ways are 25 brought into cooperating relation by rotation with the table, and means for preventing reciprocatory movement of the bed plate during a portion of the rotation of the table comprising followers and coacting ways on said bed plate which 30 pass out of cooperating relation when a plate reciprocating cam way is brought into cooperating relation with its coacting follower.
- 35 14. In a bending machine, the combination with a rotatable table, a form bed plate mounted on said table for reciprocation transversely of the axis of the table, a form on said bed plate, means for clamping an end of the work to the form, a mandrel operatively associated with said form, means for intermittently imparting reciprocating movement to said form bed plate as the table revolves comprising cam ways carried by said bed plate and a cam follower with which 40 45
- 40 45
- 50 55
- 55
- said cam ways are brought into cooperating relation by rotation with the table, and means for preventing reciprocatory movement of the bed plate during a portion of the rotation of the table comprising followers and coacting ways on said bed plate which pass out of cooperating relation when a plate reciprocating cam way is brought into cooperating relation with its coacting follower.
- 5 10 15 20 25 30 35 40 45 50 55
15. A metal bending machine comprising a rotatable table, a form plate having flange-like slideway engaging members at opposite sides thereof, said table being provided with slideways coacting therewith, and means for rapidly reciprocating said plate during the rotation of the table comprising cam tracks mounted at either end of the plate and a relatively fixed follower intermittently engageable with said cam tracks.
16. A bending machine comprising a rotatable table, a bed plate carrying a form reciprocatingly mounted on said table, and means for reciprocating said bed plate during part of each rotative cycle thereof comprising cam tracks mounted on the form plate and a cam follower intermittently engageable with said cam track to translate the form during a portion of the rotative movement of the table.
17. A metal bending machine comprising a rotatable table, a form mounted for rotative movement around the axis of rotation of said table and for slidable movement transverse to such axis, means for causing said form to rotate about the axis of rotation of the table in fixed relationship thereto during a substantial portion of the rotative movement of the table, and means for rapidly reciprocating said form during another portion of the rotation of the table.
18. In a bending machine, the combination with a rotatable table, of means for rotating the table, a form mounted on said table for reciprocation transversely of the axis of the table, a mandrel operatively associated with the form, means for preventing other than rotative movement of said form during a portion of the rotation of the table, and further means for imparting rapid reciprocating movement to said form during another portion of the rotation of said table.
19. A bending machine comprising a rotatable table, a bed plate carrying a form reciprocatingly mounted on said table, means for preventing other than rotative movement of said form during a portion of the rotation of the table, and further means for rapidly reciprocating said bed plate during another portion of the rotation of said table.
- JOHN F. FISCHER.
